(57) **CLAIM**

The ornamental design for a media streaming device, as shown and described.

DESCRIPTION

FIG. 1 is a perspective view of a media streaming device showing our new design;

FIG. 2 is a top view of the media streaming device shown in FIG. 1;

FIG. 3 is a bottom view of the media streaming device shown in FIG. 1;

FIG. 4 is a left-side view of the media streaming device shown in FIG. 1;

FIG. 5 is a right-side view of the media streaming device shown in FIG. 1;

FIG. 6 is a front-side view of the media streaming device shown in FIG. 1; and

FIG. 7 is a rear-side view of the media streaming device shown in FIG. 1.

FIG. 8 is a perspective view of a second embodiment of the media streaming device;

FIG. 9 is a top view of the media streaming device shown in FIG. 8;

FIG. 10 is a bottom view of the media streaming device shown in FIG. 8;

FIG. 11 is a left-side view of the media streaming device shown in FIG. 8;

FIG. 12 is a right-side view of the media streaming device shown in FIG. 8;

FIG. 13 is a front-side view of the media streaming device shown in FIG. 8; and,

FIG. 14 is a rear-side view of the media streaming device shown in FIG. 8.

The broken lines illustrate unclaimed portions and form no part of the claimed design. The break lines indicate undetermined length of the media streaming device. The portion between the break lines forms no part of the claimed design.

1 Claim, 8 Drawing Sheets
